UNITED STATES PATENT OFFICE.

MAX AXELROD, OF PORTLAND, OREGON, ASSIGNOR TO INTERNATIONAL APPLIANCE COMPANY, OF PORTLAND, OREGON, A CORPORATION OF OREGON.

NON-REFILLABLE BOTTLE.

Specification of Letters Patent.

Patented July 11, 1911.

997,535.

Application filed September 18, 1910. Serial No. 582,412.

To all whom it may concern:

Be it known that I, MAX AXELROD, a citizen of the United States, and a resident of Portland, county of Multnomah, State of Oregon, have invented a new and useful Improvement in Non-Refillable Bottles, of which the following is a specification.

This invention has for its object to obtain an effective device for rendering bottles of common construction non-refillable; and furthermore, to so construct and arrange the parts of my device that it may be manufactured at little expense, since the cost of manufacture has heretofore been the impediment in the general use of such devices, notwithstanding the demand therefor.

I attain my object by combining with a suitable valve mechanism, including a ball, a combined valve-shield-and-keeper, these features being fully illustrated in the accompanying drawings constituting a part hereof.

In the drawings Figure 1 is a section of a bottle neck with my invention inserted therein as in practice; Fig. 2 is a horizontal section on the lines A—A of Fig. 1; Fig. 3 is a section similar to Fig. 1, illustrating, however, a modification in construction in this, that the containing cylinder is made in two parts, and other parts are correspondingly arranged; Fig. 4 is a perspective top view of that part of my device which I term a combined valve-shield-and-keeper, with parts broken away; and Fig. 5 is a perspective view of the disk valve used by me.

The neck of the bottle *a* is of common construction, except that it is made with a contraction *b* so as to provide a shoulder to support my device; and it also has a circumferential interior groove *u* to provide means for locking my device in place, after having been inserted. The mechanism of my device is contained in the cylindrical case *c*, the bottom of which is contracted and provided with an inturned flange constituting a valve-seat *d*. On said valve-seat is a disk-valve *e*, preferably made of floating material, cork, for example, the top and bottom of which is covered by plates *q*, *q* secured in place by clamps *r*, as shown in Fig. 5. The valve is provided with peripheral ports *s* to permit the out-pouring liquid to pass the valve. On the disk-valve *e* rests a spherical weight. The cylinder *c*, as re-

presented in Fig. 1, is provided with parallel indented circumferential shoulders *g*, *m*. Between the shoulders is affixed the diaphragm *h* of my combined valve-shield-and-keeper. The diaphragm *h* of the last mentioned device is provided with a central aperture *j*, and is made with integral pendent converging arms *p*, to which is affixed by a rivet *o* the keeper, which consists of a plurality of radial arms spaced apart and arranged in the form of an inverted cup. The parts must be so relatively arranged that when the bottle is turned on its side the spherical weight will still hold the disk-valve *e* against its seat and will not permit it to open until the bottle has been sufficiently inverted to cause the spherical weight to roll into the keeper *i*. Affixed on top of the diaphragm *h*, spaced upwardly therefrom, is a circular shield *k* of greater diameter than the aperture of the diaphragm *h*, being secured in place by posts *l* on the diaphragm *h*. The shield prevents the insertion of an implement by which to dislodge the spherical weight, in an attempt to unlawfully re-fill the bottle.

The described interior mechanism of my device is in the first instance placed in the cylinder, the latter is then inserted in the neck of the bottle, and finally the circumferential indentation *n* is formed in the cylinder *c* to lock my device in place.

The arrangement of the mechanism of my device illustrated in Fig. 3 is substantially the same as described with respect to Fig. 1, except the cylinder *c* is substituted by a cylinder made of two parts *v*, *w*, telescoping in each other. The lower part *w* is formed with an inturned peripheral shoulder *z* on which rests the keeper *i*, and is further provided with a valve-seat *x* like the valve-seat *d*. The upper part *v* of the cylinder requires only a single circumferential indented shoulder *y* in order to hold my combined valve-shield-and-keeper in place.

I claim:

The combination with the neck of a bottle, of a cylinder locked in said neck and provided at the bottom with an inturned perpendicular annular flange constituting a valve seat; a floatable disk-valve provided with peripheral ports and seated on said valve-seat; a spherical weight above the disk-valve; a combined shield and keeper consisting of a diaphragm having an aper-

ture and a spanner stamped from said diaphragm and depending below the same and disposed in a central vertical plane with the aperture, means for securing the diaphragm in the cylinder, a circular shield of greater diameter than the aperture in the diaphragm and of less diameter than the inner diameter of the cylinder, said shield being spaced above and fixed to the diaphragm; and a cup shaped keeper consisting of a central plate disposed under the aperture and hav-

ing downwardly inclined radial arms spaced apart and extending from the central plate, and fastening means for securing the central plate to the spanner, said keeper 15 and spherical weight arranged to limit the lifting movement of said disk-valve.

MAX AXELROOD.
